UNITED STATES PATENT OFFICE.

RALPH S. CLARKE, OF EAST WALPOLE, MASSACHUSETTS, ASSIGNOR TO BIRD MACHINE COMPANY, A CORPORATION OF MASSACHUSETTS.

PULP-SCREEN.

1,210,906.

Specification of Letters Patent.

Patented Jan. 2, 1917.

Application filed June 26, 1916. Serial No. 105,956.

To all whom it may concern:

Be it known that I, RALPH S. CLARKE, a citizen of the United States, residing at East Walpole, in the county of Norfolk and State of Massachusetts, have invented new and useful Improvements in Pulp-Screens, of which the following is a specification, reference being had to the accompanying drawings, forming part thereof.

10 This invention has reference to improvements in machines adapted for use in screening pulp and particularly pulp to be manufactured into paper.

One of the objects of this invention is to 15 so construct a pulp screening machine that a mixture of pulp and water may be supplied to the machine in or approximately in the general direction in which precipitation of foreign matter may occur and that vibration of said pulp, to facilitate the screening action, may be effected in directions substantially transverse to said direction of supply, and also transversely of said direction of precipitation.

20 Another object of the invention is to improve the construction of pulp screens and particularly of such screens in which the vibratory or similar action on the pulp is effected through an instrumentality other 25 than or complementary to the screen.

Other objects of the invention will appear 30 from the following description.

The invention consists in the means for supplying the pulp in the direction or substantially in the direction in which precipitation of matter may occur and in mechanism for agitating the pulp.

The invention also consists in such other novel features of construction and combination of parts as shall hereinafter be 40 more fully described and pointed out in the claims.

Figure 1, represents a plan view of the improved pulp screening machine. Fig. 2, 45 represents a longitudinal section of parts of the same as taken on line 2—2 Fig. 1. Fig. 3, represents a cross sectional view of the machine as taken on line 3—3 Fig. 1.

Similar characters of reference designate 50 corresponding parts throughout.

As shown in the drawings 5 indicates the base of the machine having or sustaining the end frames 6 and 7. The end frame 6 has an opening which is defined by the 55 collar 8 and has the flange 9 extending out-

wardly from said frame 6 and the flanges 10 and 11 which extend inwardly from said frame 6, that is, toward the frame 7. This latter frame 7 has the inwardly extending flange 12 and the bearing 13 and is furnished with the bearing bracket 14.

To the flange 9 of frame 6 is secured the head 15 having the inwardly extending flange 16 and the outlet 17 which communicates with the usual box 18 which receives the screened pulp and delivers the same for the purposes of its use directly to the paper making machine or to some intermediate mechanism.

Head 15 and the portion of frame 7 defined by flange 12 constitute the ends of a tank, vat or container of which the sides and bottom are formed by the wall 19 the ends of which respectively are connected with the flanges 11 and 12 by the joint members 20 and 21 of rubber or other suitable flexible material. At its lower portion said wall 19 has the slot or opening 22 which extends longitudinally of said wall and communicates with the drain channel or member 23 fixed to wall 19 and having the outlet 24 which is adapted to be connected with a suitable means to convey the material passing from said outlet to some desired point.

Wall 19 and its member 22 are sustained by the pair of frames 25, 25 of approximately U-shape, as shown in Fig. 3 of the drawings, and partially supported at one side of the machine by somewhat flexible members or standards as 26 which are fixed to said frames 25, 25 and to brackets 27, 27 mounted on the machine base 5. At that side of the bed plate 5 remote from the brackets 27, 27 are mounted the standards 28, 28 which support the shaft 29 carrying the link 30 which has a bearing to receive the shaft 31 mounted in the frames 25, 25 at this side of the machine. Link 30 has the downwardly extending arm 32 which is engaged by the frame 33 pivotally mounted on the connecting rod 34 which has the strap or bearing 35 operatively mounted on the eccentric 36 of the shaft 37 journaled in bearings of the brackets 27, 27 and adapted to be operated in any usual manner.

Within the wall 19 is the cylindrical screen member 38 of any usual construction as to permitting the passage through openings 39, 39 in its wall of water and pulp of the desired fineness. This screen 38 is 110

mounted at one end on the head 40 having the shaft 41 journaled in the bearing 13 of the frame 7 and in a bearing of the bracket 14, and adapted to be rotated. At its discharging end this cylindrical screen 39 is mounted on the funnel member 42 which is rotatably mounted in a bearing of collar 8 of frame 6, the joints between this funnel member 42 and the flanges 10 of frame 6 and 10 of head 15 being closed respectively by the bridging elements 43 and 44 which may be of rubber or other preferably flexible material. It will thus be seen that fluid or similar material entering the cylindrical screen through the interstices of its wall will discharge through the member 42 and outlet 17 of head 15 into the box 18.

Extending from a point within the screen 39, closely adjacent to the head 40, out 20 through the open funnel member 41 is the trough 44 and above this trough 44 is located the shower pipe 45 adapted to direct water in jets upward against the wall of said screen whereby said jets of water in passing through the interstices of the wall of the screen may loosen and carry with them particles of pulp or foreign matter adhering to the exterior of the screen. A considerable proportion of the material thus 25 loosened and carried upward by the jets of water from pipe 45 enters between the walls 46, 46 of the troughs 47, 47 located above the screen and strikes the deflector 48 which directs them into said troughs 47, 30 47 from whence they pass through pipes 49, 49 into the trough 44. Such matter and water as is not thus caught by said troughs 47, 47 either is washed from the screen 39 or falls into the trough 44 and is conveyed 35 from the machine.

The pulpy or other material to be screened, by this machine, mixed with water, is supplied from the trough or troughs 50, 50 which are located above the tank or vat 45 formed by the wall 19 and have discharge or outlet slots 51, 51 extending or delivering in directions preferably parallel to said wall and to the wall of the screen 39 but at least in the general direction in which gravitation 50 or setting of heavy matter toward the outlet slot 22 of the vat occurs and, also it may be noted, that such delivery of material and the flow of the same between the wall 19 and the screen 39 is transverse to the direction 55 of agitation through the action of said wall 19.

In the operation of the machine water carrying the pulp to be treated, and usually more or less foreign matter, is supplied to 60 the troughs 50, 50 and is delivered through the slots 51, 51 thereof, as approximately vertical sheets or streams, between the sides of the wall 19 and in directions parallel to the outlet slot 22 of the vat constituted by 65 said wall 19. The flow of said water and

material carried thereby through the outlet 24 is or may be controlled by any well known means which does not in itself form part of the present invention. As a result of such supply the water and material partially fills the vat constituted by the wall 19 and some part of said water and the finer pulp passes through the interstices of the screen 39 and may ultimately overflow through the funnel 42 and outlet 17 into the box 18 for use. 70 Some proportion of the foreign matter carried by the water is of such character or specific gravity that it has a tendency to settle through the water and such matter in moving downward from the slots 51, 51 acquires inertia which is not positively opposed by any part of the machine and which tends to facilitate the passage of said foreign matter downward through the water between the wall 19 and the screen 39 until 75 said foreign matter passes through the outlet slot 22.

During some portion or the whole period in which the water and material is supplied to the machine through the slots 51, 51 shaft 90 41 is caused to rotate. This rotation of shaft 41 effects the reciprocatory motion of the connecting rod 34 through the eccentric 36 and its top 35 which motion is transmitted to arm 32 by frame 33 to effect oscillation of link 30 and vibratory motion of frames 25, 25 and the vat constituted by wall 19 in a direction generally transverse to the axis of the screen 39 and also transverse to the flow of material at and for a time after such material enters between the vibratory members constituted by the upwardly extending portions of wall 19. One of the results of thus 95 effecting the vibration or agitation of the material is that the motion of the water tends to loosen particles of pulp which adhere to the screen 39 and to force a large proportion of the pulp, of suitable size, through the interstices of the screen to the interior of said screen. Another result of 100 such agitation of the material is that the heavier foreign matter seeking to settle is freed from engagement with particles of pulp and allowed to move downward.

In order to assist in clearing the exterior 115 of the screen 39 from pulp gathered thereon and to clear the interstices of the screen, said screen is caused to rotate to subject its wall progressively to the action of the jets of water directed upwardly from the shower pipe 45. Such jets of water pass through the interstices of the screen wall and carry with them most of the pulpy material adhering to the exterior of the screen. Some of such loosened material falls back into the 120 vat and other portions of the material are carried by the force of the water jets into the troughs 47, 47 as above described.

It is to be understood that the wall 19 has the function of a vibrator member as well as 130

that of a container or vat and that the action of said wall 19 relative to the flow of the pulp or material differs from the ordinary vibrating vat.

5 While I have herein described apparatus of a somewhat specific construction it is not my intention thereby to limit my invention except as herein claimed.

Having thus described my invention I 10 claim as new and desire to secure by Letters Patent.

15 1. Apparatus of the nature described comprising a vat mounted to vibrate and having at its bottom a longitudinal outlet, a screen rotatable in said vat, a pair of supply troughs mounted above said vat and having delivery openings extending longitudinally of said vat, means to vibrate said vat and means to rotate said screen.

20 2. Apparatus of the nature described comprising a vat mounted to vibrate and having at its bottom a longitudinal outlet, a screen rotatable in said vat, a pair of troughs ex-

tending longitudinally of said screen and above the same and having between said troughs a deflector to deflect water into said troughs, means to direct water from within said screen against said deflector, means to vibrate said vat, and means to rotate said screen.

25 3. Apparatus of the nature described comprising a pair of end frames one of which has an opening, a vat located between said frames and connected flexibly therewith, said vat having an outlet at its bottom, a pair of frames supporting said vat, flexible means for sustaining said frames at one side of said vat, a pivotally mounted link for sustaining said frames at the other side of said vat, said link having a lever arm, an eccentric operated mechanism for effecting vibration, of said arm, a cylindrical screen rotatable within said vat, and means to rotate said screen.

RALPH S. CLARKE.
